UNITED STATES PATENT OFFICE.

FRANK WALLACE LEIDECKER, OF MARIETTA, OHIO.

CHECK-VALVE.

996,099.

Specification of Letters Patent. Patented June 27, 1911.

Application filed May 25, 1909, Serial No. 498,235. Renewed May 17, 1911. Serial No. 627,858.

To all whom it may concern:

Be it known that I, FRANK W. LEIDECKER, a citizen of the United States, residing at Marietta, in the county of Washington and State of Ohio; have invented a new and useful Check-Valve, of which the following is a specification.

The invention which is the subject of the present application is an improvement over the valve shown in my Patent No. 705,255 granted July 22, 1902, the object being to dispense with all screw-threads, and also to provide a structure which makes the valve easily accessible and removable together with other improved structural details to be hereinafter described and claimed.

The invention is illustrated in the accompanying drawings in which,—

Figure 1 is a longitudinal sectional view 20 of the complete structure. Fig. 2 is a perspective view of the valve carrier, seat and valve removed from its casing. Fig. 3 is an elevation of a modification; and, Fig. 4 is a longitudinal sectional view thereof.

Referring more particularly to the drawings, 25 5 and 6 denote two members of a pipe receiving union connected by an ordinary coupling ring 7. The member 5 is a tee, and the valve is located therein.

At 8 is indicated a short section of pipe 30 constituting what may be called the "valve carrier" and whose exterior diameter is smaller than the bore of the member 5 so as to leave an annular space 15 between them. The carrier is formed at one end with an outstanding annular flange 9, and has its opposite end cut obliquely to its axis to form an inclined valve seat 10, the carrier being open at both ends. The valve proper 40 is indicated at 11, and as in my former patent it has a stem 21 with a T-head 12 at its outer end journaled in a channel 19 across the carrier 8, which channel communicates through an opening 18 with the end of the

carrier to accommodate the stem. The valve 45 is held within the member 5 by clamping the flange 9 between the adjacent ends of said member and the member 6 by means of the coupling ring 7, by reason of which it 50 may be quickly put in place, or removed.

The valve is located in line with the side opening 13 of the T-member 5, in order that it may be accessible for inspection or repair. Said opening, as seen in the drawings, is placed some distance from and here about 55 midway between the ends of the member 5 in order that the latter shall not be weakened. This arrangement also enables the valve proper 11 to be removed without disconnecting the union. The opening 13 is 60 closed by a plug 14. By locating the valve as herein described it is also possible to clean the same by simply removing the plug 14, and it is not necessary to disconnect the two members of the union when access to 65 the valve for any purpose is desired. No screw-threads are required for holding the pipe section 8 in place, which greatly simplifies the structure, it being securely held between the two members 5 and 6. 70

The opening 13 is in the side of the member 5 in order that the water may run out of the same if the pipe line is to be drained.

Figs. 3 and 4 show the invention applied to an ordinary flange tee, the flange 9 of 75 the pipe 8 being held between the flanges of the tee.

What is claimed is:

The combination with a pipe receiving union, one member of which has a side opening at a distance from its ends, and a closure for the opening, of a check valve within said member comprising a relatively long valve carrier whose exterior diameter is smaller than the bore of the member and has 80 one end cut off obliquely to form a valve seat standing opposite said opening, a flange at its other end clamped in the union to hold the carrier concentric with said member, and the valve proper hinged to the inner end of 85 the carrier opposite said opening.

In testimony that I claim the foregoing as my own, I have hereto affixed my signature in the presence of two witnesses.

FRANK WALLACE LEIDECKER.
